UNITED STATES PATENT OFFICE.

HIRAM G. SEDGWICK, OF MILL VALLEY, CALIFORNIA, ASSIGNOR TO THE NATIONAL SAFETY APPLIANCE COMPANY, A CORPORATION OF CALIFORNIA.

AUTOMATIC TRAIN-STOP.

1,174,451.

Specification of Letters Patent.

Patented Mar. 7, 1916.

Application filed December 24, 1908. Serial No. 469,095.

To all whom it may concern:

Be it known that I, HIRAM G. SEDGWICK, a citizen of the United States of America, and a resident of Mill Valley, in the county 5 of Marin and State of California, have invented certain new and useful Improvements in Automatic Train-Stops, of which the following is a full and clear specification, reference being had to the accompanying drawings, in which—

Figure 1 is a diagram showing one way of applying my invention; and Figs. 2, 3 and 4 are detail cross-sections of three modified forms of cable on the line $x-x$ of Fig. 1, 15 showing the normally-alive and normally-dead conductors arranged in cable form.

This invention is designed to adapt the roadbed devices covered by my Patent No. 864,866, dated September 3, 1907, or other 20 train stop devices, for use in connection with a normally-closed-circuit block signal system of the type now in extensive use, without in the least interfering with the operation of the signal system while at the same 25 time utilizing the system to render my train-stopping mechanism less liable to derangement and more effective in preventing trains entering a pre-empted block, as more fully hereinafter set forth.

30 A further object of the invention is to utilize the normally-alive conductor to protect the normally-dead wires, so that it will be practically impossible to disrupt the normally-dead wires without at the same time 35 disrupting the normally-alive wires, whereby in case of disruption of the normally-dead wires the signals will be set to danger, thus indicating either that the system is out 40 of order or that the block ahead is pre-empted.

In the drawings I have shown this invention applied to the adjacent ends of one of the tracks of a double-track road, but it will be understood that the invention is applicable 45 to single-track roads by simply duplicating the apparatus in the well-known way. The rails of the two blocks are bonded in the usual manner and are separated by the insulation blocks a . The opposite rails of 50 each block are connected by conductors to a low-tension battery b , so that when a train passes into a block the wheels and axles of the train will complete the circuit. This 55 circuit is normally closed by conductors c which are connected to the opposite rails

and include a main relay d , this being the usual arrangement in closed-circuit signal systems. The relay d normally attracts an armature e , and this armature is connected to one of the wires f of a local circuit, the other wire being connected to a contact g , whereby when the armature is released by de-energizing the relay this circuit f will be closed and the semaphore arm h will rise to danger. This construction is also usual in this type of signal system.

When a train enters the block the wheels and axles thereof will short-circuit battery b and thus de-energize relay d whereupon the semaphore will move to danger and thus indicate that the block is pre-empted. To utilize this system in connection with my roadbed devices I extend circuit c up the road a suitable distance and include in it a supplemental relay i whose armature j is also normally attracted, thus holding open the local circuit k , one wire of which connects the armature with an insulated rail-section l at one side of the track and the other wire of which connects the contact-point m with a contact-rail n along-side of the track. It will therefore be observed that when relay i is de-energized the local circuit k will be closed between part j and part m , thus rendering the stopping circuit operative, so that 85 when the brush on the locomotive strikes contact-rail n the partial circuit k will be completed by means on the train and will automatically apply the brakes in a manner set forth in my patent or in any other suitable manner.

The stopping-rails n and l may be duplicated one or more times between their point of location and the end of the block, as is obvious, to insure additional safety, and the local circuits of each of these supplemental stopping-rails may be closed by the parts j and m or in any other suitable manner. I show one of these supplemental stopping sets of rails l' and n' and I connect these 100 rails by circuit wires k' to contacts k^2 adapted to be closed when armature e is released. I also prefer extending the supplemental circuit k' by wires k^3 to a switch k^4 which will be closed when the semaphore arm is 105 raised to danger.

It will be observed that by attaching my devices to the signal circuits in the manner set forth I do not interfere at all with their usual operation while at the same time I 110

gain the great advantage that is secured by the closed-circuit signal system, namely, that in case of derangement of any of the apparatus my train-stopping devices will be rendered operative and thus act to stop a train attempting to enter the deranged block. I am enabled also to use a series of stopping devices without appreciable additional cost at the end of each block, and this adds greatly to the safety of the system. I am also enabled to use a lighter battery on the locomotive since only sufficient current is necessary to carry through a local circuit *k* to stop the train. There are many other important advantages in this new system that will be obvious to one skilled in the art.

The letter *c'* indicates loops of the normally-closed circuit *c* which are extended and carried around the normally-dead wires *k* and *k'* of the stopping system. The wires of these loops are arranged closely adjacent to the normally-dead wires in such manner that it will be practically impossible to disrupt the normally-dead wires without at the same time disrupting the normally-alive wires, whereby the disruption of the normally-dead wires will set the signals to danger and thus show that the system is deranged.

In order to protect the normally-dead wire fully it is preferred to arrange the same in a single cable with the normally-alive wires, as shown in Figs. 2, 3 and 4. In Fig. 2 the three conductors are each incased in a non-conducting covering and the two outer or live conductors are made wider than the dead conductor so as to afford a better protection therefor. In Fig. 3 the same arrangement is shown except that the conductors are all arranged in a single casing, and in Fig. 4 the conductors are in the form of wires arranged in a single non-conducting casing.

Having thus fully described my inven-

tion, what I claim as new, and desire to secure by Letters Patent, is:—

1. A railway signaling and stopping system embodying normally-open and also normally-closed circuits, the conductors of the normally-closed circuit being arranged in close juxtaposition to the normally open circuit so as to thereby mechanically protect the same and thus reduce to a minimum the chance of the open circuit being ruptured without at the same time rupturing the closed circuit. 55

2. In a railway block system signal devices, a closed signal controlling circuit, an open train-stopping circuit on the roadbed adapted to be closed when the signal devices are operated, and means whereby the conductors of the closed circuit are brought into mechanically protective relation with the conductors of said open circuit. 60

3. The combination with train-stopping devices embodying a normally-dead conductor, of a normally-closed signal controlling circuit and a coöperating signal, said normally-closed signal controlling circuit having a loop formed in it, the branches of this loop being arranged in mechanically protective relation to said normally-dead conductor. 70

4. The combination with train-stopping devices embodying a normally-dead conductor, of a normally-closed signal controlling circuit and a coöperating signal, said normally-closed signal controlling circuit having a loop formed in it, the wires of said loop being arranged on opposite sides of and in a single cable with said normally-dead conductor. 75 80

In testimony whereof I hereunto affix my signature in the presence of two witnesses 85 this 10th day of December 1908.

HIRAM G. SEDGWICK.
